UNITED STATES PATENT OFFICE.

HENRY BELL, OF BALTIMORE, MARYLAND.

BOTTLE-WRAPPER.

SPECIFICATION forming part of Letters Patent No. 257,642, dated May 9, 1882.

Application filed March 10, 1882. (No model.)

To all whom it may concern:

Be it known that I, HENRY BELL, of Baltimore, in the State of Maryland, have invented a new and useful Improvement in Bottle-Wrappers, of which the following is a full, clear, and exact description, reference being had to the annexed drawings, forming part of this specification.

This invention consists of a novel bottle wrapper or envelope made of suitable strips of material laid across each other at the center and secured together, and provided with means for binding the envelope around a bottle, substantially as hereinafter described.

In the accompanying drawings, Figure 1 is a side elevation of my improved wrapper, showing the manner of securing it around a bottle. Fig. 2 is an inside view of the bottom of the wrapper partly broken away, and Fig. 3 is a view showing the manner of constructing the wrapper from rushes or reeds.

In constructing the wrapper A, I cut the stalks or leaves or other material a little more than twice the length of the bottle to be covered and place them across each other at the center. When a sufficient number of stalks, &c., have been thus arranged, they are secured together by means of a tack or clasp, a, and two circular pieces of pasteboard or felting, b, about the size of the bottom of the bottle, which are arranged on opposite sides of the covering material and fastened thereto by means of the clasp. The ends of the stalks or flags are then bent upward over one of the pieces of pasteboard in such manner as to form a hollow cylindrical envelope for a bottle.

To provide a means for securing the wrapper around a bottle, I cut a suitable number of the flags employed in the construction of the wrapper about one-half longer than the

rest, and after a small band, c, made of any suitable material, has been passed over the ends of the flags to bind them close to the neck of the bottle, the said longer ends are bent back toward the bottom of the bottle, and another band, d, larger than the first, is passed over the entire wrapper to about the center thereof, to hold the longer ends down and prevent the band c from becoming accidentally displaced.

When rushes or reeds are employed they are to be sewed together to form strips of suitable width, as shown in Fig. 3, and the strips are to be arranged and secured together in the manner above described. In the latter case two or more tacks, a, may be used to secure the parts together.

Having thus described my invention, what I claim as new, and desire to secure by Letters Patent, is—

1. A bottle-wrapper made of lengths of vegetable fiber, which are secured together at their centers and adapted to be bent up from the bottom to the neck of a bottle, substantially as shown and described.

2. A bottle-wrapper made of lengths of vegetable fiber, which are secured together at their centers between pieces of pasteboard or felting, substantially as shown and described.

3. A bottle-wrapper composed of suitable pieces of material, which are secured together at the center and bent up around the bottle and confined by a band, and having a number of the strips made longer than the rest and bent back over the said band and confined by another band inclosing the wrapper, substantially as shown and described.

HENRY BELL.
